UNITED STATES PATENT OFFICE.

WILLIAM F. KELLETT, OF CHICAGO, ILLINOIS.

DESIGN FOR A PLASTER CENTER-PIECE.

SPECIFICATION forming part of Design No. 14,006, dated June 26, 1883.

Application filed December 1, 1882. Term of patent 14 years.

To all whom it may concern:

Be it known that I, WILLIAM F. KELLETT, a citizen of the United States, residing at Chicago, in the county of Cook and State of Illinois, have invented and produced a new and original Design in Plaster Center-Pieces for Rooms, of which the following is a true and correct specification, reference being had to the accompanying engraving.

5 My design is circular in form; and it consists in a ring, A, with a border consisting of diamond-shaped ornaments on the outer circumference thereof, with the body or surface containing volutes B, with scallop-work and conventional poppy-buds C, and having a rosette, 15 D, in the center of said design, all in relief, as shown in the accompanying engraving.

I claim—

A circular design in plaster, having a ring with a border consisting of diamond-shaped 20 ornaments, with the body or surface containing volutes with scallop-work and conventional poppy-buds and central rosette, substantially as shown and described.

WILLIAM F. KELLETT.
